Franklin Bennett*

INVENTOR.

Alfred E. Smith

United States Patent Office.

ALFRED E. SMITH, OF BRONXVILLE, NEW YORK.

Letters Patent No. 72,555, dated December 24, 1867.

IMPROVEMENT IN AXLES FOR WAGONS.

The Schedule referred to in these Letters Patent and making part of the same.

TO ALL WHOM IT MAY CONCERN:

Be it known that I, ALFRED E. SMITH, of Bronxville, Westchester county, and State of New York, have invented certain new and useful Improvements in Axles for Wagons and other vehicles; and I do hereby declare that the following is a full description of the same.

The nature of my invention consists in forming the screw-tap of a compensating axle with a flattened or grooved face, and combining therewith a D-shaped washer, so as to be carried around with the axle, and thus form a bearing for the screw-nut to act against, in drawing the hub on it, instead of acting directly against the end of the metal box in which it runs, as is commonly the case.

But to describe my invention more particularly, I will refer to the accompanying drawings, forming a part of the specification, the same letters of reference, wherever they occur, referring to like parts.

Figure 1 is a side view of the axle and metal box.

Figure 2 is a longitudinal cut section of the same.

Figure 3 is a detached view of the axle or spindle.

Figure 4 is a transverse cut section of the spindle, through the line $z z$, fig. 2.

Figure 5 is a detached view of a metal washer.

Figure 6 is an end view of the spindle.

Letter A is a metal box, having at its back end an enlarged chamber, B, for the support of the shoulder C of the axle, and a packing, D, for preventing the parts from grinding away or cutting out. In the front end of the metal box is formed an annular collar, or diaphragm, E, for the purpose of reducing the size of the opening in the front end of the box. The object of this is to form a wall, and thus make a receptacle, F, behind it, and in front of the end of the spindle G, for an oil-chamber. This spindle is made of less length in its bearing-surface than the length of the metal box, and has an elongated screw-tap, H, extending through the opening in the diaphragm, to engage in the screw-nut I at the end of the box. Between the screw-nut and the face of the diaphragm, and on the screw-tap, is a metal washer, J, having a section cut out or otherwise notched on its inner circumference, to correspond with the flattened or notched side or sides of the screw-tap, so as to prevent the same from turning on the screw-tap. The object of this is to prevent the washer from rotating, and thus, when the screw-nut is turned up, the box is forced up the spindle to compensate for the shrinkage or wearing away of the leather washers in the box, preventing thereby the screw-nut from unloosing, when the wheels of the vehicle are backed, as would be the case if the nut were drawn tightly against the end of the box, and the washer not prevented from turning on the screw-tap. It will be obvious that a cavity for the washer J may be formed in the end of the nut, instead of in the end of the box. In either case the effect is the same. It will also be obvious that one or more washers, J, may be used, and leather and metal used together, and, therefore, do not restrict myself to the use of a single metal washer, but purpose to use one or more, and leather and metal together, as circumstances may require, to accomplish the result aimed at, to wit, making an anti-rattling compensating axle for wagons and other vehicles.

Having now described my invention, I will proceed to set forth what I claim and desire to secure by Letters Patent of the United States.

I claim the D-shaped washer J, in combination, with the screw-cap H and diaphragm F, made and operating substantially as hereinbefore set forth.

ALFRED E. SMITH.

Witnesses.
